United States Patent Office

Des. 185,749
Patented July 28, 1959

185,749

KITE

Clyde H. Gossett, Van Nuys, Calif.

Application February 13, 1959, Serial No. 54,597

Term of patent 14 years

(Cl. D34—15)

Fig. 1 is a perspective view of a kite embodying my new design;

Fig. 2 is a side view of the kite, looking in the direction of the arrow 2 of Fig. 1;

Fig. 3 is a bottom view of the kite;

Fig. 4 is a front view of the kite; and

Fig. 5 is a rear view of the kite.

I claim:

The ornamental design for a kite, as shown.
